D. W. HUGHES

Hemp Brake.

No. 12,456.

Patented Feb. 27, 1855.

UNITED STATES PATENT OFFICE.

D. W. HUGHES, OF NEW LONDON, MISSOURI.

IMPROVEMENT IN HEMP-BRAKES.

Specification forming part of Letters Patent No. 12,456, dated February 27, 1855.

To all whom it may concern:

Be it known that I, D. W. HUGHES, of New London, in the county of Ralls and State of Missouri, have invented a new and useful Improvement in Machinery for Breaking Hemp, Flax, &c.; and I do hereby declare that the following is a full, clear, and exact description of the same, reference being had to the accompanying drawings, forming part of this specification, in which—

Figure 1 is a side elevation of a brake constructed according to my invention, and Fig. 2 is a plan of the same.

Similar letters of reference indicate corresponding parts in both figures.

This invention consists in a certain arrangement and application of and mode of operating a number of teeth or breakers which are employed to break and separate the woody from the fibrous portion of the material.

To enable those skilled in the art to make and use my invention, I will proceed to describe its construction and operation.

A is a strong frame, of a convenient height for the material to be fed by hand to the teeth or breakers, which work immediately above it. B B and C are the breakers, which somewhat resemble heavy blunted knives, placed in an upright position. The two breakers B B are attached to the front ends of two horizontal levers, D D, which work on fulcrum *a a*, secured in a fixed position in the frame. The back ends of these levers are connected by pins *b b* to two toggle-arms, E E, whose connecting-pin *c* is extended upward with an eye to fit to a fixed straight horizontal guide-bar, *d*, which stands in a line at right angles to an imaginary line drawn between *a a*. The two levers D D have springs F F applied to them in such a way as to throw apart the breakers B B toward the position indicated in Fig. 2 in red outline, and the connecting-pin *c* of the toggle-joint has a cord or chain, G, attached to it, and running backward from it around a pulley, *e*, which is placed in a fixed standard, H, the said cord or chain then running forward over another pulley, *f*, in a fixed standard, I, and descending to a treadle, J, so placed that an operator can keep his foot upon it while he feeds the material to the machine. By the pressure of his foot upon the treadle, the operator can draw back the pin *c* and extend the

toggle-joint to draw the breakers B B toward each other until they nearly meet, as shown in black outline in Fig. 2. The breaker C is attached to a horizontal bar or slider, K, which receives a rapid reciprocating motion through a connecting-rod, L, from a crank, M, on the driving-shaft N, at the rear end of the machine, which receives a constant rotary motion from any prime mover. This movement drives the breaker C between and draws it back from the breakers B B.

In operating with this machine, the unbroken material which is supposed to have been previously wholly or partly rotted is placed, while the breaker C is drawn back across the blunt edges of the breakers B B, which are brought closer together or farther apart by the treadle, according as the material is finer and softer or coarser and harder, or the bunch is smaller or larger. The action of the breaker C by driving the material against and between those B B first cracks and then breaks up the wood and detaches it from the fiber. As the operation progresses, the operator gradually presses down the treadle with his foot to make the breakers B B approach each other, and as the fiber is divested of woody matter, it is allowed to be driven by the breaker C farther in between the breakers B B. By the time the latter breakers arrive nearly in contact, the woody matter will be entirely broken, and the operator then raises his foot from the treadle to allow the breakers to be thrown apart by the springs F F previously to his feeding the material onward to submit another portion to the action of the breaker C; and in this manner the operation proceeds, a fresh portion of unbroken material being presented as soon as one portion has been sufficiently operated upon. It will be observed by reference to Fig. 2 of the drawings, that as the breakers B B approach each other they also advance toward C, and allow it to enter farther between them, which is desirable, as the material becomes more pliable.

The advantage possessed by this machine over others is that the person who handles the material can adapt the breakers to any kind of material, whether well rotted or not, and either to a large or small bunch, and in fact has perfect control of the breakers while the machine is running.

Instead of only two breakers B B and one C, any other number of each may be employed if found desirable.

What I claim as my invention, and desire to secure by Letters Patent, is—

Arranging and applying the breakers B B so that they may be brought while the machine is in operation to the proper distance apart to suit the nature of the material to be

operated upon, and may be caused to approach each other or nearer to the line of operation of their corresponding breaker C as the operation progresses, substantially as herein set forth.

D. W. HUGHES.
